CLAIM

The ornamental design for an electrical terminal, as shown and described.

DESCRIPTION

FIG. 1 is an upper left perspective view of the electrical terminal;

FIG. 2 is an upper rear perspective view of the electrical terminal;

FIG. 3 is a lower left perspective view of the electrical terminal;

FIG. 4 is a front elevational view of the electrical terminal;

FIG. 5 is a left side elevational view of the electrical terminal;

FIG. 6 is a right side elevational view of the electrical terminal;

FIG. 7 is a rear elevational view of the electrical terminal;

FIG. 8 is a top plan view of the electrical terminal; and,

FIG. 9 is a bottom plan view of the electrical terminal.

The dashed lines are for illustration of environmental subject matter only and form no part of the claimed design.
